UNITED STATES PATENT OFFICE

156,552

PAPER NAPKIN HOLDER

Joseph F. Meyer, St. Paul, Minn.

Application September 8, 1947, Serial No. 141,258

Term of patent 14 years

(Cl. D44—24)

To all whom it may concern:

Be it known that I, Joseph F. Meyer, a citizen of the United States, residing at St. Paul, county of Ramsey, State of Minnesota, have invented a new, original, and ornamental Design for a Paper Napkin Holder, of which the following is a specification, reference being had to the accompanying drawings, forming part thereof.

Fig. 1 is a perspective view of a paper napkin holder, showing my new design;

Fig. 2 is a top plan view;

Fig. 3 is a bottom plan view;

Fig. 4 is a view in front elevation; and

Fig. 5 is a view in side elevation thereof.

I claim:

The ornamental design for a paper napkin holder, substantially as shown.

JOSEPH F. MEYER.
